Primary Examiner — Cynthia Ramirez*Assistant Examiner* — Llorellys Martinez(74) *Attorney, Agent, or Firm* — Neal O. Willmann(57) **CLAIM**

The ornamental design for a detachable wrist band, as shown and described.

DESCRIPTION

FIG. 1 is front elevation view of a detachable wrist band showing my new design, the rear view being identical thereto;

FIG. 2 is a top plan view thereof, the bottom plan view being identical thereto;

FIG. 3 is right elevation view thereof, the left side elevation view being a mirror image thereof; and,

FIG. 4 is another top plan view thereof, showing the detachable wrist band in a detached state for clarity of illustration.

The broken lines in the drawings illustrate portions of the detachable wrist band that form no part of the claimed design.
